UNITED STATES PATENT OFFICE.

HENRY GORRIS, OF CLEVELAND, OHIO, ASSIGNOR OF ONE-HALF TO JOHN N. HAHN, OF SAME PLACE.

DESIGN FOR A COAL-SCUTTLE.

SPECIFICATION forming part of Design No. 25,419, dated April 21, 1896.

Application filed March 14, 1896. Serial No. 583,262. Term of patent 14 years.

To all whom it may concern:

Be it known that I, HENRY GORRIS, a citizen of the United States, residing at Cleveland, in the county of Cuyahoga and State of Ohio, 5 have invented and produced a new and original Design for Coal-Scuttles, of which the following is a specification, reference being had to the accompanying drawing, showing a part thereof.

10 In the accompanying drawing I show a perspective view of a coal-scuttle embodying my new design.

The leading feature of my design consists in the contour or outline of my design as a 15 whole rather than in any single distinguishing characteristic. Thus, first of all, the body 2 of the design is peculiar and novel in that it is fashioned to the outline of a section of a perfect cylinder or tube with straight par- 20 allel lines from the decorative base B to the decorative and ornamental top C, the said straight lines beginning at 3 at the bottom and terminating at 4 at the top. This straight plain-surfaced body, however, is relieved and 25 ornamented by the annular beads or ribs 5 and 6 and decorative figures 7 between the same on the sides of the scuttle.

A second feature of the complete design is the decorative base B, which flares somewhat from the point 3 and is relieved between its 30 upper and lower portions by annular swells and depressions alternately and enlarging toward the bottom.

A third feature of the complete design is the artistically shaped and tapered top or 35 cover C, projected toward the front of the scuttle on straight converging lines of some- 40 what different inclination to a horizontal plane top and bottom and terminating in a ring-shaped extremity 9, which lies at an in- clination to the side of the body 2 and outside the vertical plane thereof. A decorative figure 10 relieves the otherwise plain surface of the back of the said top or cover C.

What I claim is—

45 The design for a coal-scuttle, substantially as herein shown and described.

Witness my hand to the foregoing specification this 20th day of February, 1896.

HENRY GORRIS.

Witnesses:

H. T. FISHER,
H. E. MUDRA.
